J. M. BRINGMAN

SPARK PLUG

Filed Nov. 20, 1925

UNITED STATES PATENT OFFICE.

JOHN M. BRINGMAN, OF BUTTE, MONTANA.

SPARK PLUG.

Application filed November 20, 1925. Serial No. 70,340.

The present invention relates to spark plugs, particularly well designed to facilitate the priming of an engine cylinder in connection with which the plug is used, and is an improvement on United States Patent #1,333,897, granted to me on March 16, 1920.

The primary object of the invention is to provide an improved priming spark plug of extremely simple construction and which plug will prevent leakage of gas outwardly therethrough during the operation of the engine.

A further object of the invention resides in the provision of a spark plug including the usual porcelain insulator or core through which the central electrode of the plug extends, and which central electrode is shiftable longitudinally through the porcelain in a manner for permitting of a volatile fuel placed in the head of the plug to flow about the firing point of the electrode.

Other objects and advantages of the invention will be apparent during the course of the following detailed description, taken in connection with the accompanying drawing, forming a part of this specification, and in which drawing—

Figure 1 is a side elevation of the improved spark plug constructed in accordance with my invention.

Figure 2 is a central longitudinal section through the plug on line 2—2 of Figure 1, and showing the movable elements of the plug in a position for preventing leakage of gas outwardly through the plug during operation of the engine.

Figure 3 is a central longitudinal section through the plug and showing the same in an open position for permitting of a volatile priming fuel being passed through the plug for spreading over the firing point of the central electrode.

Figure 4 is a cross section through the plug on line 4—4 of Figure 1; and

Figure 5 is an enlarged fragmentary sectional view of the upper portion or end of the plug.

Referring to the drawing in detail, and wherein similar reference characters designate corresponding parts throughout the several views, 1 indicates the metal shell of the spark plug in which porcelain or insulating core 2 is secured as by the usual type of packing nut 3.

The core 2 is provided with a centrally disposed bore 4, the lower end of which opens out into a pocket or recess 5 opening at the lower end of the porcelain and forming a shoulder 6.

Fitting within the bore 4 is a metal tube or sleeve 7 having a screw threaded upper portion projecting past the top of the porcelain and having formed adjacent its lower end an annular flange 8 below which a valve seat 9 extends. Thus it will be seen that the shoulder 6 provides an abutment for the annular flange 8 of the tube 7. Threaded upon the upper end of the tube 7 is a terminal binding nut 10 which when turned into binding engagement with the upper end of the porcelain 2, draws the annular flange 8 into binding engagement against the shoulder 6 for forming an effective seal. The binding nut 10 may be formed for receiving the terminal conductor 11.

Fitting within the tube 7 and projecting past each end thereof, is a central electrode 25 for the spark plug having a stem portion 12 not less than semi-circular shape in cross section and which semi-circular stem portion is of greater length than the length of the tube 7. Formed on the electrode and spaced below the lower end of the stem portion 12, is a valve 13 having a flat upper face for seating engagement with the valve seat 9 when the electrode is in a raised or closed position. Extending from the lower side of the valve 13, and which valve is of less diameter than the inner diameter of the recess 5, is a firing point or portion 14 which is adapted to extend into sparking relation with the outer electrode 15. A head 16 is formed at the upper end of the stem portion 12, and which head is of a size equal to the inner diameter of the tube 7 for permitting of the electrode being slid through the tube in the assembling of the spark plug.

A priming cup or cap 17 having an axially disposed threaded sleeve 18 for threaded engagement with the upper threaded end of the tube 7 is secured to the central electrode 25 as by a pin 19 extending through the electrode 25 at a point immediately below the head 16. Thus it will be seen that upon rotation of the cap 17, that the electrode will be moved longitudinally within the tube 7 for seating and unseating of the valve 13. It is preferred that the cap 17 be formed of a suitable insulating material such as

fiber or the like, so as to permit of the same being rotated during operation of the engine with which the plug is associated when desiring to determine if all of the plugs are functioning properly.

The pin 19 aside from forming a connection between the cap 17 and the central electrode, acts when the cap is rotated in one direction for seating the valve upon the 10 valve seat 9 and closing the passageway 20 through the tube 7, and upon rotation in the opposite direction engages with the upper end of the tube for limiting the inward movement of the electrode 25.

15 It may be here stated that the object in having the stem portion 12 of not less than semi-circular shape in cross section, is to prohibit lateral shifting of the stem within the tube 7, and which lateral shifting would 20 prevent the valve centering portion 21 from entering the lower open end of the tube. Such formation of the stem portion 12 also prevents lateral shifting of the firing portion 14 with respect to the sparking point 25. 15. It will also be observed a space exists between the head 16 and the sleeve 18 at all times, so that the priming fluid upon being poured into the upper concave surface of the cap 17, may readily pass into the passageway 20.

When it is desired to prime a cylinder of an engine with which the spark plug is used, the cap 17 may be rotated in a right hand direction and which action through the 35 threaded sleeve 18 will feed the central electrode 25 downwardly into a position as illustrated in Figure 3, thus opening the lower end of the passageway 20 through the tube 7. The gasoline or other priming fluid may 40 then be poured into the concaved upper face of the cap 17 whence it will flow through the passageway 20 and around the firing point 14. After a sufficient amount of the priming fluid has been poured through the 45 plug, the cap 17 may be rotated in a left hand direction and which action through the pin 19 will raise the valve 13 to a closed position upon the valve seat 9 and thus close the passageway 20.

50 From the foregoing description it will be apparent that an extremely simple and efficient priming plug for use in connection with internal combustion engines has been provided, embodying a central electrode 55 shiftable longitudinally through the spark plug for the opening and closing of a passageway extending through the spark plug.

Various minor changes may be made to the specific form of invention herein shown and described, without departing from the spirit of the invention or the scope of the following claims.

I claim:

55 1. In a spark plug, the combination of an insulating core provided with a central bore,

a metal sleeve fitting in the bore and having an externally threaded end portion projecting past the outer end of the core, a central electrode extending through the sleeve and having an intermediate flattened stem portion of greater length than the sleeve for forming a passageway through the sleeve, and having an enlarged portion at its inner end of greater diameter than the sleeve and forming a valve head for seating engagement with the inner end of the sleeve, a cap threaded upon the outer end of the sleeve, and means rigidly connecting the cap to the outer end of the electrode whereby the electrode will be rotated and moved longitudinally within the sleeve upon rotation of the cap.

2. In a spark plug, the combination of an insulating core provided with a central bore, a sleeve extending through the bore and having an externally threaded end portion projecting past the outer end of said core, a central electrode embodying a flattened stem portion, extending through the sleeve and having an enlarged portion at the inner end of its stem forming a valve for seating against the inner end of the sleeve and having the opposite end of the flattened stem portion projecting past the outer end of the sleeve, means for securing the sleeve in the bore of the insulating core, a cap having a threaded bore into which a portion of the flattened stem portion projects, threaded upon the outer end of the sleeve and having a concaved upper surface sloping toward said threaded bore, and a pin connecting the cap to the stem portion of the electrode at a point outwardly of the outer end of the sleeve.

3. In a spark plug, the combination of an insulating core provided with a central bore, a sleeve fitting in said bore having a seat at its inner end and having an externally threaded portion extending past the outer end of said core, a central electrode extending through said sleeve embodying an intermediate semi-circular shaped stem portion having an enlarged valve head formed at its inner end for seating against the inner end of said sleeve and having its outer end extending past the outer end of the sleeve and provided with a head of a diameter no greater than the internal diameter of said sleeve, a cap threaded upon the outer end of the sleeve, and means connecting the cap to the outwardly projecting end of the electrode for seating and unseating of the valve head upon rotation of said cap.

4. In a spark plug, the combination of an insulating core provided with a central bore, a sleeve extending through the bore and having an externally screw threaded outer end, a central electrode extending through the sleeve having an enlarged portion at its inner end forming a valve head for seating

against the inner end of the sleeve, an intermediate semi-circular shaped stem portion extending from a point close adjacent said valve head to a point past the outer end of the sleeve and a head portion at the outer end of the stem portion, said stem portion forming a passageway through the sleeve and being of greater length than the sleeve, a cap threaded upon the outer end of the sleeve having a concaved upper surface for directing a fluid placed in the cap to said passageway, and means rigidly connecting the cap to the outer end of the electrode for imparting longitudinal shifting movement to the electrode upon rotation of the cap.

5. In a spark plug, the combination of an insulating core provided with a central bore, a sleeve extending thru the bore and having an externally threaded end portion projecting past the outer end of said core, a central electrode fitting in said sleeve embodying a flattened stem portion of greater length than said sleeve having a valve formed at its inner end and a head provided at its outer end normally disposed outwardly of the outer end of the sleeve, a priming cap having a threaded bore for threaded connection with the threaded projection of said sleeve, said threaded bore to receive the

head and a portion of the flattened stem portion of the electrode, and a pin connecting the cap and electrode, said pin extending transversely through the threaded bore of the cap and through the electrode at a point directly beneath its head.

6. In a spark plug, the combination of an insulating core provided with a central bore, a sleeve fitting in the bore and having an externally threaded portion projecting past the outer end of the core, a central electrode provided with a flattened stem portion, extending through the sleeve and having a valve head formed at its inner end for seating engagement with the inner end of the sleeve, and means for moving the electrode longitudinally within the sleeve for seating and unseating of the valve head for opening and closing of a passageway through the sleeve, comprising a cap of insulating material provided with an axial bore, an internally threaded metallic sleeve fitting in said bore for threaded engagement with the threaded end of said sleeve, and a pin extending transversely through the cap and sleeve and the outer portion of the electrode for securing of the sleeve within the cap and the cap to the electrode.

JOHN M. BRINGMAN.
